(57) **CLAIM**

The ornamental design for a medical device for chondrectomy, as shown and described.

DESCRIPTION

FIG. 1 is a left side elevational view of a medical device for chondrectomy showing my new design;

FIG. 2 is a right side view thereof;

FIG. 3 is a bottom plan view thereof;

FIG. 4 is a top plan view thereof;

FIG. 5 is a right side perspective view thereof; and,

FIG. 6 is a top, right side perspective view thereof.

The broken lines shown in FIGS. 1-6 illustrate portions of the medical device for chondrectomy that form no part of the claimed design.

1 Claim, 6 Drawing Sheets
